INVENTOR.
Irving Barkan

BY

J. Kaplan
ATTORNEY.

UNITED STATES PATENT OFFICE

IRVING BARKAN, OF PHILADELPHIA, PENNSYLVANIA

TOOTHBRUSH

Application filed August 19, 1931. Serial No. 558,126.

This invention relates to a tooth cleaning brush and gum massaging device made of rubber and is especially adapted for the use of children.

5 The main object of the invention is to provide a device of this kind having means to clean the teeth and separate means to massage the gums.

Another object of the invention is to provide 10 a means at the end of the brush handle to clean the spaces between the teeth.

A further object of the invention is to provide a longitudinal reinforcing rod for stiffening the brush and handle.

15 Other objects will appear as the disclosure progresses. The drawing is intended to merely indicate a possible embodiment of the invention. It is obvious that the actual needs of manufacture may necessitate certain mechanical changes. It is therefore not intended 20 to limit the invention to the embodiment illustrated but rather to define such limits in the appended claims.

For a more general understanding of the 25 invention attention is called to the drawing. In the drawing like reference characters denote like parts throughout the specification.

Figure 1 is a top view of the brush.

30 Figure 2 is a side view thereof.

Figure 3 is a bottom view.

Figure 4 is a section on line 4—4 of Figure 1.

Referring now to the drawing in detail, 35 numeral 1 designates the handle, 2 the brush foundation and 3 the brush bristles for cleaning the teeth. On the side of the foundation opposite to the brush bristles is a set of triangular shaped teeth 4 used for massaging the gums. At the outside end of the handle is 40 a disk 5, having bevelled sides and provided with a series of pointed teeth 6 on its periphery. The purpose of the teeth 6 is to clean the crevices between the teeth of the user.

45 Passing through the center of the brush is a rod 7 having an eye 8 at the end adjacent the disk 5. Registering with this eye is a hole 9 passing through the handle. The purpose of this hole is to provide means for hanging up the brush on a nail or hook.

50 The entire brush except, of course, the re-

inforcing rod is made of moulded rubber. The brush bristles 3 are tapered and arranged in staggered relation to each other.

It will thus be seen that I have provided a 55 simple and efficient brush for the purpose specified. The brush can be cleaned and sterilized without being in any way damaged.

Having described my invention, I claim

1. In a brush of the class described, the 60 combination of a handle, of a disk at the outside of said handle, and a series of pointed teeth on the periphery of said disk for cleaning the crevices between the teeth of the user.

2. In a brush of the class described, the 65 combination of a handle, of a disk at the outside end of said handle, said disk having bevelled sides, and a series of pointed teeth on the periphery of said disk for cleaning the crevices between the teeth of the user.

In testimony whereof I affix my signature. 70
IRVING BARKAN.
